(57) **CLAIM**

The ornamental design for a footwear outsole, as shown and described.

DESCRIPTION

FIG. 1 is a bottom plan view of a footwear outsole showing our new design;

FIG. 2 is a top plan view thereof;

FIG. 3 is a left side elevational view thereof;

FIG. 4 is a right side elevational view thereof;

FIG. 5 is a front elevational view thereof; and,

FIG. 6 is a rear elevational view thereof.

The broken lines shown in FIGS. 2 and 6 define the boundary of the design. The broken lines and the area within, form no part of the claim.
